The ornamental design for a clamp with round lamp, as shown and described.

DESCRIPTION

FIG. 1 is a front perspective view of a clamp with round lamp when closed according to our new design.

FIG. 2 is a rear perspective view of the clamp with round lamp when closed.

FIG. 3 is a front view of the clamp with round lamp when closed.

FIG. 4 is a rear view of the clamp with round lamp when closed.

FIG. 5 is a left side view of the clamp with round lamp when closed.

FIG. 6 is a right side view of the clamp with round lamp when closed.

FIG. 7 is a top view of the clamp with round lamp when closed.

FIG. 8 is a bottom view of the clamp with round lamp when closed.

FIG. 9 is a front perspective view of the clamp with round lamp when opened according to our new design.

FIG. 10 is a rear perspective view of the clamp with round lamp when opened.

FIG. 11 is a front view of the clamp with round lamp when opened.

FIG. 12 is a rear view of the clamp with round lamp when opened.

FIG. 13 is a right side view of the clamp with round lamp when opened.

FIG. 14 is a left side view of the clamp with round lamp when opened.

FIG. 15 is a top view of the clamp with round lamp when opened.

FIG. 16 is a bottom view of the clamp with round lamp when opened.

FIG. 17 is a front perspective view of the clamp with round lamp when extended according to our new design.

FIG. 18 is a rear perspective view of the clamp with round lamp when extended.

FIG. 19 is a front view of the clamp with round lamp when extended.

FIG. 20 is a rear view of the clamp with round lamp when extended.

FIG. 21 is a right side view of the clamp with round lamp when extended.

FIG. 22 is a left side view of the clamp with round lamp when extended.

FIG. 23 is a top view of the clamp with round lamp when extended; and,

FIG. 24 is a bottom view of the clamp with round lamp when extended.

This design is directed to a clamp with round lamp.
